UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A LAMP-FOUNT HOLDER.

SPECIFICATION forming part of Design No. 24,611, dated August 20, 1895.

Application filed July 22, 1895. Serial No. 556,829. Term of patent 3½ —

To all whom it may concern:

Be it known that I, FRANZ YOKEL, of Meriden, in the county of New Haven and State of Connecticut, have invented a new Design 5 for a Lamp-Fount Holder, (Case A;) and I do hereby declare the following, when taken in connection with the accompanying drawing and the letters of reference marked thereon, to be a full, clear, and exact description of the o same, and which said drawing constitutes part of this specification, and represents a perspective view of a lamp-fount holder embodying my design.

This invention relates to a design for a lamp- 5 fount holder, and it consists in the configuration and ornamentation as shown in the accompanying drawing.

The holder is of a bowl-like character with an outwardly-flared ornamental rim A, contracted at its lower end to a band B. The 20 bowl is ornamented by grotesque masks C, below which is a circumferential floriated band D, surmounted by lattice-work E, which is inclosed by a series of elaborate scroll and leaf ornamentations, all as shown in the accompanying illustration.

I claim—

The design for a lamp-fount holder as herein described and shown in the accompanying illustration.

In testimony whereof I have signed this specification in the presence of two subscribing witnesses.

FRANZ YOKEL.
